ATTORNEY

UNITED STATES PATENT OFFICE.

CHARLES H. MILLER AND SAMUEL A. McDONALD, OF DECATUR, TEXAS.

SASH-FASTENER.

SPECIFICATION forming part of Letters Patent No. 408,920, dated August 13, 1889.

Application filed March 25, 1889. Serial No. 304,606. (No model.)

To all whom it may concern:

Be it known that we, CHARLES H. MILLER and SAMUEL A. McDONALD, of Decatur, in the county of Wise and State of Texas, have 5 invented a new and useful Improvement in Window-Fasteners, of which the following is a full, clear, and exact description.

Our invention relates to an improvement in window-fasteners, and has for its object to 10 provide a device of simple, durable, and economical construction, capable of attachment to any window, and of convenient manipulation.

A further object of the invention is to provide 15 a device whereby a window may be effectually locked in an open, in a closed, or in any desired position.

The invention consists in the novel construction and combination of the several 20 parts, as will be hereinafter more fully set forth, and pointed out in the claim.

Reference is to be had to the accompanying drawings, forming a part of this specification, in which similar letters and figures of reference 25 indicate corresponding parts in all the views.

Figure 1 is a partial front elevation of a window - frame, illustrating the application thereto of the device. Fig. 2 is a vertical section 30 through the window, the device being in side elevation. Fig. 3 is a section taken partially on line $x-x$ of Fig. 1; and Fig. 4 is a vertical section of the bracket, the thumb-lever being in side elevation.

In carrying out the invention a strip or bar 35 10, preferably of spring metal, is provided, having its ends bent slightly downward and outward, whereby when the said ends of the bar are attached to the stile of the window-frame, as illustrated in Fig. 1, the body of the bar will be elevated a distance from said stile, as best shown in Fig. 2. The strip or bar 10 is preferably rectangular in cross - section. To the inner face of the window-frame 11, in front of the sash, a bracket 12 is secured, which bracket is preferably angular, as illustrated 40 in Figs. 1 and 4, consisting of a vertical member a and a horizontal member a' .

When the bracket is made in the form above 45 described, it is attached to the window-frame by passing screws or equivalent fastening

devices through the vertical member into the said frame, apertures 13 being produced in the said vertical member to that end, as shown in Fig. 3. The horizontal member of the 55 bracket, which constitutes the body thereof, is provided with a vertical aperture or opening 14, the walls whereof are inclined from the center outward, as illustrated at 15 in Fig. 3, whereby the said aperture or opening is 60 wider at the top than at the bottom. Before attaching the bar 10 to the stile of the window-sash the lower end of the said bar is passed through the opening or aperture 14 of the bracket, and in the vertical member of 65 the bracket one end of a thumb-lever 16 is hinged to have a vertical movement, the opposite end of which lever extends parallel with and beyond the horizontal member of the bracket, as best shown in Figs. 1 and 4. 70 The thumb-lever 16, immediately above the opening 14 in the bracket, is provided with an integral preferably wedge-shaped lip 17, concavo-convex in cross-section, as best shown in Fig. 3.

In operation, when the window has been carried to the desired position, the thumb-lever being out of engagement with the horizontal member of the bracket, to retain or lock the window in such position, the thumb-lever is pressed down, whereupon the lip 17 enters the opening 14 in the horizontal member of the bracket and contacts with the inner or under face of the bar 10. This movement of the lever is readily accomplished by 75 reason of the yoke-like form of the bar 10 and by reason of the fact that the lever passes from the vertical member of the bracket outward to the rear of the bar, as shown in Fig. 1. As the upper portion of the opening 14 is 80 wider than the lower portion, and as the lip is concavo-convex in cross-section, when the said lip is forced down into the bracket-opening, the strip or bar 10 is kinked, as illustrated in Fig. 3. Thus a curve is produced 85 at the point of contact with the lip, and at said point of contact the said bar is firmly wedged between the fixed surface of the lip and one tapering wall of the opening.

It will be readily observed from the foregoing description and by reference to Fig. 3 of the drawings that when the parts of the de-

vice are thus locked the window can neither be raised nor lowered until the thumb-lever is again elevated.

Having thus described our invention, we claim as new and desire to secure by Letters Patent—

In a window-fastener, the combination, with an angle-bracket having an opening produced in its horizontal member wider at its top than at its bottom, and an essentially yoke-shaped bar passed through the said opening, of a thumb-lever hinged in the vertical member of the bracket, extending over

and parallel with the horizontal member of said bracket, and a lip integral with the under edge of the lever, concavo-convex in cross-section, and capable of entering the opening in the bracket and contacting with the inner or under face of the yoke-like bar, all combined for operation substantially as shown and described.

CHAS. H. MILLER.
SAMUEL A. McDONALD.
